UNITED STATES PATENT OFFICE.

JOACHIM B. SCHARF AND MAX ROTH, OF CHICAGO, ILLINOIS.

BATTERY TERMINAL CLAMP.

Application filed September 9, 1927. Serial No. 218,529.

This invention relates to certain novel improvements in battery terminal clamps and has for its principal object the provision of an improved construction of this character 5 which will be highly efficient in use and economical in manufacture.

Among the salient objects of the invention is to provide a clamp for the terminal of a storage battery which will assure a positive 10 connection between itself and the terminal post.

A still further object of the invention is to provide a simple means for releasably attaching the clamp to a terminal post of a 15 storage battery.

Other objects will appear hereinafter.

The invention consists in the novel combination and arrangement of parts to be herein-after described and claimed.

20 The invention will be best understood by reference to the accompanying drawings, showing the preferred form of construction and in which:

Fig. 1 is a perspective view of a clamp embodied in the invention;

Fig. 2 is a top plan view of a clamp showing a modified form of construction;

Fig. 3 is a sectional detail view taken substantially on line 3—3 of Fig. 2; and

30 Fig. 4 is a sectional detail view taken substantially on line 4—4 of Fig. 2.

Referring more particularly to the drawing, the clamp 10 includes a jaw 11 which is adapted to be clamped on the terminal post 35 of a storage battery. This clamp 10 provides a split sleeve 12 for the reception of one end portion of a cable which is secured in the sleeve by solder or the like. The jaw 11 provides a central opening 13 and the walls 14 of this opening have formed thereon a plurality of spaced teeth or prongs 15. The ends of the jaw include bearing heads 16 carrying a bolt 17 on which is threaded a nut 18 where by to facilitate clamping the jaws to the 40 terminal post.

To apply the clamp to the terminal post the jaws are positioned in place and clamped on the post and as the nut is threaded upon the bolt 17 the jaws will be drawn together and 50 the prongs forced into the terminal post thereby assuring positive connection between the clamp and the post.

In Figs. 2 to 4 inclusive we have shown a modified form of construction and in this 55 construction the jaws of the clamp are indi-

cated at 19 and the sleeve at 20. A wedging cap is indicated at 21 and this wedging cap is substantially U-shaped in cross section to provide limb portions 22 which are pivotally secured to the jaws through the medium of 60 bolts 23. The bight portion 24 of the cap provides a lip 25 beneath which a screw driver or other tool is adapted to be placed for pivoting the cap in an upward position to permit expansion of the jaws by inserting 65

the tip of the screw driver or other tool in the space 26 between the jaws and spreading the jaws apart. The inner walls of the limb portions have formed thereon tapered lugs 27. These lugs 27 taper downwardly and 70 when the cap is pivoted down upon the jaws these tapered lugs will act upon the jaws and force the jaws toward each other to clamp upon the terminal post 28. By this arrangement it will be seen that the usual bolt such as 75

is illustrated in Fig. 1 and indicated at 17 is eliminated. It has been found that due to corrosion or acid eating of the bolt the bolt often cannot be loosened. By the provision of the cap it is manifest that when formed of 80 non-corrosive material the cap can be easily pivoted into and from jaw clamping position.

It is intended that the clamp illustrated in Fig. 1 and also in Fig. 2 be formed of a non-corrosive material of a well-known ingredient.

The jaws 19 in the modified form of construction likewise may be provided with the teeth or prongs 15.

While we have illustrated and described 90 the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what 100 we claim as new and desire to protect by Letters Patent is:

1. In a clamp for the terminal post of a storage battery including a sleeve adapted for the reception of one end portion of a 105 cable, jaws formed as an integral part of the sleeve and including a central opening, penetrating members carried by the wall of the opening and adapted to penetrate into the wall of the terminal post, and a member piv- 110

otally carried by the jaws and including wedge shaped elements operable on the jaws for forcing the jaws into clamping position upon the post and for forcing the penetrating members into the post.

5. 2. In a clamp for the terminal post of a storage battery, a sleeve adapted for the reception of one end portion of a cable, jaws formed as an integral part of the sleeve, and

including a central opening, and a member 10 pivotally carried by the jaws and including wedge elements operable on the jaws for forcing said jaws into clamping engagement upon the post of a storage battery.

In testimony whereof we affix our signatures.

JOACHIM B. SCHARF.
MAX ROTH.
